Primary Examiner — Vy N Koenig*Assistant Examiner* — Elizabeth Anne Glassberg(74) *Attorney, Agent, or Firm* — John A. Yirga, Esq.; Watts Law LLC(57) **CLAIM**

The ornamental design for an animal pen, as shown and described.

DESCRIPTION

FIG. 1 is an upper front perspective view of an animal pen, illustrating our ornamental design;

FIG. 2 is a lower rear perspective view thereof;

FIG. 3 is a first side view thereof;

FIG. 4 is a front elevation view thereof;

FIG. 5 is a second side view thereof;

FIG. 6 is a rear elevation view thereof;

FIG. 7 is a top plan view thereof; and,

FIG. 8 is a bottom plan view thereof.

The broken lines in the figures illustrate portions of the animal pen that form no part of the claimed design.

1 Claim, 8 Drawing Sheets(56)
